(57) **CLAIM**

The ornamental design for an artificial Christmas tree base cover, as shown and described.

DESCRIPTION

FIG. 1 is a front perspective view of an artificial Christmas tree base cover shown in a use condition showing our new design.

FIG. 2 is a front elevational view of the artificial Christmas tree base cover.

FIG. 3 is a rear elevational view of the artificial Christmas tree base cover.

FIG. 4 is a right side elevational view of the artificial Christmas tree base cover.

FIG. 5 is a left side elevational of the artificial Christmas tree base cover.

FIG. 6 is a top plan view of the artificial Christmas tree base cover; and,

FIG. 7 is a bottom plan view of the artificial Christmas tree base cover.

Any broken lines shown in FIGS. 1-7 are included for the purpose of illustrating environmental elements only and form no part of the claimed design.
